DIAPHRAGM CONTROL MECHANISM

Peter Parke, Chicago, and Harold W. Hollands, River Forest, Ill., assignors to The Pullman Company, Chicago, Ill., a corporation of Illinois

Application December 19, 1935, Serial No. 55,166

11 Claims. (Cl. 105—22)

The invention relates to means for supporting vestibule diaphragms and face plates of vehicles whereby movement of the diaphragms is positively controlled and undesirable shifting of the diaphragm and associated parts prevented either vertically or laterally.

The principal object of the invention is to support and positively control the diaphragm assemblies on railway cars so as to prevent lost motion and noise during train movement.

Another and important object of the invention is the prevention of wear on the supporting structure and on certain of the working parts of the diaphragm assembly.

Another object of the invention is the prevention of lateral movement of the diaphragm assembly.

The invention has for its further object the provision of an improved type of upper buffering spring in which rubbing friction is avoided and the spring ends cushioned to allow for relative motion.

A still further object of the invention is the provision of an improved cushioned coupler supporting arrangement.

The foregoing and other objects are attained by the mechanism illustrated in the accompanying drawings in which—

Fig. 1 is a front elevational view of a diaphragm fitted with the control mechanism of the invention as applied to a railway car;

Fig. 2 is a side elevational view thereof;

Fig. 3 is a sectional view taken on line 3—3 of Fig. 1 illustrating in plan the diaphragm and upper buffering spring arrangement and the supporting mechanism;

Fig. 4 is a plan view in section taken on line 4—4 of Fig. 1 showing the platform arrangement having portions broken away better to illustrate the method of shimming the buffer side stems to prevent lateral movement of the diaphragm at its base;

Fig. 5 is a view similar to Fig. 3 showing the diaphragm parts in the position assumed during passage of the car about a curve of short radius;

Fig. 6 is an enlarged fragmentary plan view of an end portion of the upper buffering spring partly in section taken on the line 6—6 of Fig. 7;

Fig. 7 is a vertical sectional view of the spring end arrangement taken on the line 7—7 of Fig. 6;

Fig. 8 is a perspective view of one of the stay rod assemblies showing the parts in their disassembled relation;

Fig. 9 is an enlarged fragmentary sectional view through a stay rod taken on line 9—9 of Fig. 1

and illustrating the parts in their assembled operative relation;

Fig. 10 is a central longitudinal sectional view taken on line 10—10 of Fig. 1 and illustrates the method of supporting and cushioning the coupler to prevent the transmission of noise from this source;

Fig. 11 is a cross section through a buffer side stem taken on line 11—11 of Fig. 4 showing the lateral shimming of the stem in end elevation;

Fig. 12 is a perspective view of a side liner and adjusting shim for the buffer side stems;

Fig. 13 is a side elevational view of a railway car equipped with a modified form of the invention;

Fig. 14 is a perspective view similar to Fig. 8, of the modified form of stay rod assembly illustrating the parts in their disassembled relation;

Fig. 15 is an enlarged elevational view of a portion of one of the modified stay rod end connections showing the parts in their operative relation; and

Fig. 16 is a similar view illustrating the parts in section.

Ordinarily, in the regular operation of railway cars, undue clearance, as the result of wear, develops between the upper and lower guiding surfaces of the buffer side stem pockets, and although the diaphragm and face plate may be supported by some form of spring suspension, jolting of the car or friction between the face plates of associated cars in a train may cause the side stems to slam up or down in their guiding pockets in the buffer end sill casting or to slap sidewise therein as a result of lateral thrusts and create noise disturbing to passengers in the cars and especially objectionable in sleeping car service.

The present invention contemplates the provision of members which, though positively controlling movement of the diaphragm assembly, shall permit the in-and-out movement necessary to diaphragms of connected cars in a train together with means for preventing lateral shifting of the buffer face plate and associated parts at the base of the assembly.

In the drawings, 10 represents a railway car having a diaphragm assembly 11 including the face plate 12 and bellows-fold diaphragm 13 of any suitable construction, and forming with a similar diaphragm on an adjacent car a continuous, enclosed passage between cars in a train. A buffer angle 14 connects the lower extremities of the face plate and is provided with a foot plate 16 fixed thereto and completing the passageway between cars. As best shown in Fig. 4, buffer side

stems 17 and 18 are pivoted to the buffer angle at 19 and extend rearwardly thru openings 29 and 30 in the buffer end sill 15 and penetrate backstops 21 and 22 secured to the center sills 26 and 5 are prevented from withdrawing therefrom by nuts 31 and 32. The backstops 21 and 22 provide rear abutments for the springs 23 and 24 which encircle the respective side stems 17 and 18 and have operative thrust engagement therewith by 10 means of shoulders 27 providing limiting stops for washers 28 to force the face plate 12 always outwardly against the similar action of a face plate of an adjoining car.

The side stems are free to reciprocate longitudinally through the openings 29 and 30 in the end sill under action of associated cars in a train but are limited in their lateral movement and, therefore, the face plate also, by side liners 33 15 adjustably mounted in the side stem openings 29 and 30. The liners have laterally extending flanges 34 engaging the rear face of the buffer end sill 15 at one side of the respective openings 29 and 30 through the medium of which they are removably secured to the end sill by bolts 36 20 extending entirely through the sill. To facilitate proper adjustment of the side liners with respect to the side stems, shims 37 are provided, as desired, between the outside sill walls of the openings 29 and 30 and the liners 33 and are secured 25 to the end sill in a manner similar to that in which the liners are secured. The shims are flanged laterally at the front face of the end sill as at 38 and are secured by nuts 39 taking the bolts 36. After the nuts 39 are drawn up tight, the 30 flanges 38 are bent at right angles to themselves closely adjacent the nuts, as indicated at 41, thereby to act as a lock to prevent reverse rotation of the nuts and insure the permanency of the assembly. As best shown in Figs. 4 and 11, 35 the holes 35 in the front and rear faces of the end sill 15 are elongated laterally to permit ready shifting of the bolts 36 as additional shims 37 are added or removed for the adjustment of liners 33.

The side liners 33 are mounted in opposing 40 relation only upon one side of each of the side stems 17 and 18 and, as the outer ends of the stems are rigidly connected by the buffer angle 14 acting as a strut therebetween, they will serve effectively to prevent lateral motion of the side 45 stems and of the diaphragm and positively to guide the assembly in normal operation to prevent excessive lost motion.

Stay rods 65 are provided upon opposite sides of the diaphragm assembly and are secured at 50 their lower ends to the lowermost extremities of the face plate 12 and at their upper ends to the end wall 44 of the car. These rods normally support the diaphragm and resist any tendency thereof to move vertically in either direction or 55 to cant laterally and cause the face plate and associated parts at all times to move in a fixed path determined by the relatively slight arc described by the rods 65 about their supporting brackets 66.

The supporting brackets 66 are secured to the end wall of the car preferably at the position of end posts 67 and fixed thereto by bolts 68, and, if desired, they may be welded to the end sheet 44 as at 69. The lower brackets 71 are secured 60 to the face plate 12 and buffer angle 14 by rivets 72. Both brackets 66 and 71 comprise attaching portions 73 and supporting flanges 74 which are perforated at 76 for the accommodation of rods 65.

The stay rods comprise tubular columns 65

having end closure members 77 inserted therein and secured by rivets 78. The closure members provide opposed upper and lower shoulders 79 and 81, respectively, each having an oppositely extending, threaded shank portion 82 adapted for insertion through the perforations 76 in the brackets 66 and 71. A rigid metal washer 83 is positioned about each of the shanks 82 in engagement with the respective shoulders 79 and 81, and flexible washers 84, of rubber or the like, are interposed between the metal washers and the respective flanges 74 of the supporting brackets 66 and lower attaching brackets 71. Similar rubber washers are disposed upon the opposite side of each of the flanges 74 and additional rigid washers 83 placed thereon in position to be engaged by the clamping cap nuts 87 whereby the stay rods 65 are flexibly connected, top and bottom, to the end wall of the car and the diaphragm face plates respectively and adapted to resist 20 upward thrusts of the diaphragm as well as to act as a support therefor. The cap nuts 87 are secured in place by locking pins 85.

The flexible washers 84 are each provided with surface plates 88 and 89 and divider plate 90 for reinforcement and to reduce the amount of vertical movement of which the individual units are capable. The units 84 are also provided with annular rubber flanges 86 which, when placed in opposing relation in their assembled position surrounding the shanks 82, enter the openings 76 in the brackets 66 and 71 and entirely insulate the shanks 82 from metallic contact with the respective brackets, whereby friction between the parts, with its resultant wear and noise, is eliminated and ready pivoting of the rods about the brackets assured. The annular flange 86 of each washer is reinforced by a concentric inner flange 91 forming an integral part of surface plate 89.

The supporting rod assemblies are installed 40 with the flexible units 84 under a substantial initial compression applied by the cap nuts 87, and all inward and outward movement of the diaphragm assembly will necessarily have to be accommodated by the flexing of units 84 about 45 the flanges 74 of the attaching brackets 66 and 71. In actual practice, the cap nuts 87 are drawn up just short of the maximum compressibility of the flexible units 84 so that insofar as vertical movement is concerned there is practically no 50 variation in the distance between attaching brackets 66 and 71 whereby the diaphragm face plate will be guided in a substantially fixed orbit about the upper brackets 66 as a center, the brackets 66 and 71 acting as pivot points in the 55 operation of the stay rods 65.

As best shown in Fig. 11, the buffer side stems 18 are supported by the stay rods clear of the bottom wall of the side stem openings 30 in the end sill 15 so that the stems will contact only the 60 side liners 33 in a straight inward-and-out motion instead of the combined in-and-out and constant vertical slamming up and down heretofore resulting in excessive wear and undue noise and causing the diaphragm at the top to flop from 65 side to side as a result of the lost motion. By the use of the stay rods of the present invention, the diaphragm face plate is held rigid at both sides and transverse movement thereof at the top thereby prevented and, with the side stem liners 70 at the bottom, is guided in a definite movement without lost motion in either direction.

In Figs. 13 to 16, inclusive, is illustrated a modified form of the stay rod arrangement in which ball and socket universal joints are uti- 75

lized to accomplish the purpose of flexible washers 84 above described. In this arrangement the rods 165 have end closure members 177 providing shoulders 178 and 181 and oppositely extending shanks 182 as before. The supporting brackets 173 are provided with ball joints 174, perforated at 176 to receive the shank members 182, and are secured to the end wall 44 of the car and to the face plate 12 at the top and bottom respectively.

10 In the application of the arrangement to a car, as shown in Fig. 13, socket members 184, in the form of concave washers, are placed about the shank portions 182 in engagement with the respectively upper and lower shoulders 179 and 181 15 in oppositely disposed relation and in position to engage the ball joints 174 of the brackets 173 as the shank portions 182 enter the perforations 176. Additional socket members 184 are placed about the shank portions 182 upon opposite sides 20 of the ball joints 174 and the entire assembly secured by cap nuts 187.

The perforations 176 in the ball joints 174, taking the shank portions 182 of the strut members 165, are oppositely tapered, as best shown 25 in Fig. 16, with the smallest diameter at the center of the ball joints so that, in operation, the strut members are permitted a universal movement.

It will be seen that the weight of the dia- 30 phragm is supported on the top and bottom socket members 184 last applied, through cap nuts 187, placing the rods 165 in tension, but upward thrusts of the face plate are resisted by the socket members first applied and place the struts 35 in compression so that vertical movement of the diaphragm in either direction is resisted at each side thereof and the tendency to rock laterally thereby eliminated and complete control of the diaphragm positively assured.

40 At the upper end of the diaphragm assembly, inward movement of the diaphragm face plate 12 is resisted by a full elliptic upper buffer spring 42. The spring 42 is composed of two semi-elliptic springs 46 and 47, one of which is secured 45 to the face plate 12 by means of a bolt 43 having a countersunk head, and the other secured to the end wall 44 of the car through the medium of bolts 45. At their adjoining ends, the semi-elliptic springs are held in non-metallic engage- 50 ment by resilient units 48 designed to take the place of the usual shackle members and which prevent frictional contact between the two springs, as best shown in Figs. 3, 5, 6 and 7. The units 48 are removable and comprise each a 55 flanged bearing plate 49 bent in the form of a general U-configuration having side walls 51 and 52 extended in parallel relation and a metal receptacle 53 in juxtaposed complementary relation to the plate 49 and formed of a plate 56 bent 60 to provide walls 54 and 55 disposed substantially parallel to the walls 51 and 52 of the bearing member 49 and having end closure plates 57 welded thereto to form a pocket 58 for the reception of the spring ends of unit 46. Disposed between the 65 members 49 and 56 and overlapping their respective ends as at 59 and 61, there is inserted a cushion of live rubber 60 vulcanized to the surfaces of the two opposing plate members. The units thus developed provide composite members 70 affording metallic bearing surfaces for wear and intermediate non-metallic vibration absorbing cushions for uniting the wear parts.

The unit 48 is generally cylindrical in form and the main leaf of spring unit 46, at its ends, 75 is made straight and inserted in pocket 58,

while the main leaf of spring 47 is bent and adapted to engage about the semi-cylindrical portion of bearing plate 49 between the edge flanges 62 and 63 whereby the unit is interlocked with the spring ends and held from displacement. 5 As the springs are compressed, the spring member 46 remains fixed in respect to the unit 48 due to its insertion in pocket 58, but the curved end of member 47 slides relatively to the unit about its semi-cylindrical portion until the portion 64 10 thereof, tangential to the curve of the unit, engages the outside surface of side wall 51. Shocks, relative vertical action of the two springs and any twisting or canting action thereof will be absorbed noiselessly by the cushion 60. 15

In order to insure further noise prevention and as best shown in Figs. 1 and 10 of the drawings, the car coupler 95 is supported upon a sound-deadening, resilient cushion 96 which prevents metal-to-metal contact between the coupler and buffer end sill 15 and is seated upon the coupler saddle 97 slidably mounted upon the coupler carrier 98 secured to said sill. Securely to hold the cushion 96 in position upon the saddle 97 and to protect it from abrasion, it is covered by a 25 metal wear plate 99 flanged downwardly over the front and rear faces of the saddle at 101 and 102 respectively. An additional resilient cushion 100 of greater width than that beneath the 30 coupler to allow for the different relative positions of the coupler with respect thereto is placed immediately above the coupler thereby to restrict excess movement of the coupler and prevent the transmission of noise to the car body. The cushion 100 is of rubber vulcanized to a 35 backing plate 106 and is secured to the end sill casting 15 by bolts 107, the nuts 103 of which are locked in position and prevented from reverse rotation by locking washers 104 bent at 40 105 to engage one face of the nuts. The cushion 40 96 is also of rubber vulcanized to a backing plate 94 but is merely seated upon the saddle 97 between the upstanding flanges 92 and 93 and held in position by the cover plate 99 engaging the front and rear faces of the coupler saddle. 45 By the use of these cushions, the coupler is noiselessly and resiliently supported upon the carrier and undue lost motion thereof yieldably resisted.

From the foregoing, it will be noted that there 50 has been provided a diaphragm supporting mechanism in which has been eliminated all vertical and lateral movement between the points of attachment on the body of the car and at the face plate, so that such movement between 55 the diaphragms of adjacent cars takes place only between contacting surfaces of the respective face plates. Thus arranged, the mechanism prevents lost motion in the respective assemblies and eliminates, at its source, the greatest amount 60 of noise on a railway car and in which the wear on the working parts has been reduced to a minimum and the operation of the diaphragm and associated parts generally improved.

The suspension of the buffer stems to clear the bottom and top sides of their respective openings 29 and 30 in the buffer sill 15 and the separation of the shank of coupler 95 from contact with buffer sill parts by cushions 96 and 100 respectively beneath and over the coupler, provide 70 complete insulation for the buffer end sill assembly from the noise producing sources incident to operation of stem-supported diaphragms and direct-supported couplers having metal-to-metal contact with the buffer sill. 75

What is claimed is:—

1. A railway car vestibule diaphragm construction comprising a face plate and mechanism connecting the face plate to the car body comprising vertically spaced brackets on the car body and face plate and means connecting said brackets allowing in-and-out and angular movement of the face plate with respect to the car body and adapted to prevent vertical displacement of the face plate with respect to the car body, said means including a rigid element between the brackets and including devices at the ends of the rigid element, said devices pivotally securing said brackets in said means and maintaining surfaces of said brackets in engagement with surfaces of said means.
2. A railway car vestibule diaphragm construction including a face plate, mechanism connecting the face plate to the car body comprising vertically spaced brackets on the car body and face plate and means connecting said brackets allowing in-and-out and angular movement of the face plate with respect to the car body and adapted to prevent vertical displacement of the face plate with respect to the car body, said means including a rigid element between the brackets and including devices at the ends of the rigid element, said devices pivotally connecting said brackets and element and maintaining surfaces of said brackets in engagement with surfaces of said means, and means for preventing lateral displacement of the face plate.
3. A railway car vestibule diaphragm construction comprising a face plate and mechanism connecting the face plate to the car body comprising spaced brackets on the car body and face plate and means connecting said brackets allowing in-and-out and angular movement of the face plate with respect to the car body and adapted to prevent vertical displacement of the face plate with respect to the car body, said means including a rigid element between the brackets and clamping devices at the ends of the rigid element including non-metallic members pivotally securing said brackets in engagement with said rigid element.
4. A railway car vestibule diaphragm construction comprising a face plate and mechanism connecting the face plate to the car body comprising vertically spaced brackets on the car body and face plate and means connecting said brackets including a rigid element between the brackets, non-metallic members interposed between the brackets and the ends of the rigid element, and means compressing said non-metallic members whereby the connection between the brackets and the rigid element flexes sufficiently to allow in-and-out and angular movement of the face plate with respect to the car body and prevent relative vertical displacement.
5. A railway car vestibule diaphragm construction comprising a face plate and mechanism connecting the face plate to the car body comprising vertically spaced brackets on the car body and face plate and means connecting said brackets including a rigid element between the brackets and a connection for the rigid element and brackets comprising a non-metallic resilient bushing compressed between each bracket and the rigid element, said bushings flexing sufficiently to allow in-and-out and angular movement of the face plate with respect to the car body and prevent relative vertical displacement.
6. A railway car vestibule diaphragm construction comprising a face plate and mechanism con-

nnecting the face plate to the car body comprising vertically spaced brackets on the car body and face plate and means connecting said brackets including a rigid element between the brackets and a connection for the brackets and rigid element comprising reduced end portions of said element entering relatively large holes in the brackets and resilient, non-metallic bushings in said holes surrounding said reduced end portions, said bushings flexing sufficiently to allow in-and-out and angular movement of the face plate with respect to the car body and prevent relative vertical displacement.

7. A railway car vestibule diaphragm construction comprising a face plate and mechanism connecting the face plate to the car body comprising vertically spaced brackets on the car body and face plate and means connecting said brackets including a rigid element between the brackets and a connection for the brackets and rigid element comprising reduced end portions of said element entering relatively large holes in the brackets and having threaded terminals, non-metallic bushings in said holes surrounding said reduced end portions, and a nut taking each threaded terminal to compress said bushings whereby said bushings flex sufficiently to allow in-and-out and angular movement of the face plate with respect to the car body and prevent relative vertical displacement.

8. A railway car vestibule diaphragm construction comprising a face plate and mechanism connecting the face plate to the car body comprising vertically spaced brackets on the car body and face plate and means connecting said brackets allowing in-and-out and angular movement of the face plate with respect to the car body and adapted to prevent vertical displacement of the face plate with respect to the car body, said means including a ball formed on each bracket and a rigid element having at each end a pair of sockets pivotally clamping one of said balls.

9. A railway car vestibule diaphragm construction comprising a face plate and mechanism connecting the face plate to the car body comprising vertically spaced brackets on the car body and face plate and means connecting said brackets allowing in-and-out and angular movement of the face plate with respect to the car body and adapted to prevent vertical displacement of the face plate with respect to the car body, said means including a rigid element having reduced end portions, an apertured ball formed on each bracket and penetrated by one of said reduced end portions, and socket members associated with the rigid element and clamping said balls, whereby the brackets are pivotally clamped to the rigid element.

10. A railway car vestibule diaphragm construction comprising a face plate and mechanism connecting the face plate to the car body comprising vertically spaced brackets on the car body and face plate and means connecting said brackets allowing in-and-out and angular movement of the face plate with respect to the car body and adapted to prevent vertical displacement of the face plate with respect to the car body, said means including a rigid element having reduced end portions, threaded at their terminals, an apertured ball formed on each bracket and penetrated by one of said reduced end portions, an inner socket member associated with the rigid element and receiving each of said balls, and an outer socket member taking each threaded terminal and pivotally clamping said balls to said rigid element.
